DOOR HOLDER

Max Shoolman and Sidney M. Bergman,
Brookline, Mass.

Application November 20, 1934, Serial No. 753,867

6 Claims. (Cl. 292—338)

The present invention relates to door holders. As distinguished from the usual door holder, the present invention relates to a type of holder which swings from a pivoted position and is operative 5 in the same direction at different places for releasing the holder and also for securing it in place.

The invention applies in particular to a door which comes up against a door frame and more particularly to a door in which there is a tendency 10 for the door to swing from an open to a closed position. Doors of this type are those which naturally swing closed by gravity or in which some particular means are used, as for instance, a door check or a spring to close the door after 15 it is opened. The holder of the present invention in these cases is applied to that face of the door which is foremost as the door swings to a closed position. The holder of the present invention will not only prevent the door from chattering when 20 it is closed, but will also hold the door open in any desired position. There is also provided in the present invention means for controlling the holding element from either side of the door itself. This is an important feature in the present invention when it is desired to be able to control or 25 operate the door holder from either side of the door.

The invention has other features which will appear more clearly from consideration of the description given below in connection with the drawing in which:

Figure 1 shows the invention as applied to the lower part of a door showing a portion of the door in section. Figure 2 shows a view looking at 35 the door from right of Figure 1. Figure 3 shows a perspective looking from the left of Figure 1, and Figure 4 shows another perspective looking from the right of Figure 1.

In Figure 1 the lower part of the door is indicated at 1 through which there is made a circular hole 2 which is the only cutting necessary in the door itself to allow the holder to be attached to it. The holder is mounted on a base plate 3 which has extending therefrom a pair 45 of bearing plates 4 and 5, in which there is pivoted the pins or shafts 6 and 7. The pin 6 pivots or carries the holding element 8 which is composed of a hub 9 surrounding the pivot 6, an arm 10 extending downwardly from the hub, a foot 50 pedal 11 projecting outwardly from the arm 10, and a floor engagement member 12 at the bottom of which may be fitted a rubber cap 13 or some suitable means to offer friction with the floor. The holding element 8, in addition is provided with an upwardly extending arm 14 which

is pivoted at its end to the bell crank lever 15 in the pivot 16. The bell crank lever 15 is formed with two fork elements through which the shaft or pivot 17 passes. The bell crank lever 15 is also pivoted to the shaft or pin 7 which passes 5 through a hole in the lever and is supported in the bearing plates 4 and 5 previously described. The top of the lever 15 is provided with a foot rest 18 which is pressed by the foot to raise the bearing plate 13 bearing against the floor. By lowering the foot pedal 18, the top end of the arm 14 is forced inwardly against the door and the contact element 13 with the floor thereby swings upward with the pivot or pin 6 as a center 10

There is also provided in the hub 9 a threaded 15 portion 20 in which the rod or bar 21 is threaded. This bar 21 extends through the opening 2 in the door and is shaped at the other end in the form of a pedal 22 which when pressed also raises the contact piece 13. The rod 21 may be threaded 20 over a considerable portion and may be cut in such lengths to accommodate the thickness of the door.

In order to lower the contact piece 13 from the side of the door at which the pedal 22 is 25 placed, there is provided a pivoted lever 23 which is pivoted in the plate 24 fastened by screws 25 to the outside of the door. This pivot is indicated in Figure 2 by the line 26. The lever 23 is forked at the end 27, the fork surrounding the shaft 21 30 as indicated in Figure 2. At the opposite end of the lever 23 there is provided a pedal 28 permanently attached to the lever and operating in a slot 29 in the plate 24. When the lever 22 is pressed down, the pedal 28 is raised upward 35 and therefore the holding member is in such a position that it may be lowered when the pedal 28 is pressed. In order to lower the contact element 13 from the left side of the door as shown in Figure 1, the foot may be pressed on the foot 40 rest 11, in which case the lever 22 on the other side of the door, is raised, and therefore in a position so that the member 13 may be released. If the element 28 is omitted and the lever 23 45 omitted, then the holding member may be released from the right side of the door by raising as well as lowering the lever 22. If elements No. 21 and No. 22 are omitted the step may be operable only from the left side of the door as shown in Figure 1, in which case the step will 50 be pressed down by pressing on the pedal or step 11 and raised by pressing down on the lever 18.

Having now described our invention, we claim:

1. A door holder having in combination, a floor engaging member, and individual means on each 55

- side of the door one set of said means adapted to be forced downward for rendering the member effective and the other for rendering the member ineffective.
5. A door holder having in combination a pivoted floor engaging member, and individual means on each side of the door adapted to be forced downward for actuating the member in the same direction about its pivot.
10. 3. A door holder having in combination a pivoted floor engaging member, the floor engaging member having two arms one of which extends through the door, and means on opposite sides of the door connected with the respective arms for actuating the floor engaging member.
15. 4. A door holder having in combination a pivoted floor engaging member having an arm and a pivoted member connected on one side of the pivot with the arm, the pivoted members having 10
pedals on the non-connected sides of the pivots.
- 20.

5. A door holder having in combination a pivoted floor engaging member having an arm extending through the door, and a pivoted member having on one side of the pivot a recess in which the arm is received, the pivoted members having 5
pedals on the non-connected sides of the pivots.

6. A door holder having in combination a pivoted floor engaging member having two arms one of which extends through the door, a pivoted member connected on one side of the pivot with the extending arm, the pivoted members having 10
pedals on the non-connected sides of the pivot arms for actuating the said other arm, and the floor engaging member having a projecting member 15
adapted to be engaged by the foot to actuate the floor engaging member.

MAX SHOOLMAN.

SIDNEY M. BERGMAN.
